(57) CLAIM

The ornamental design for a watch face, as shown and described.

DESCRIPTION

FIG. 1 is a top plan view of a watch face showing our new design; and,

FIG. 2 is a perspective view of the watch face with an unclaimed bracelet shown in broken lines.

The broken line showing of the bracelet for the watch in FIG. 2 is for illustrative purposes only, merely showing the types of bracelets which can be used, and forms no part of the claimed design.
